[57] **CLAIM**

The ornamental design of a welding connector for a conduit, as shown.

DESCRIPTION

FIG. 1 is a perspective view taken from the bottom and one side of a welding connector for a conduit showing my new design;

FIG. 2 is a perspective view taken from the top and a side 90 degrees from the side shown in FIG. 1;

FIG. 3 is an elevational view of the side shown in FIG. 1, the opposite side being the same as the side shown; FIG. 4 is a top plan view thereof; and FIG. 5 is a bottom view thereof.
